MUSICAL TOY

William R. Allen, 2029 N. Kenmore Ave.,
Los Angeles, Calif.

Filed Aug. 17, 1964, Ser. No. 81,308

Term of patent 14 years

(Cl. D34—15)

FIG. 1 is a perspective, partially front elevational view of a musical toy, showing my new design;

FIG. 2 is a side elevational view of the side of the toy concealed from view in FIG. 1;

FIG. 3 is a bottom plan view;

FIG. 4 is a front elevational view; and

FIG. 5 is a rear elevational view.

I claim:

The ornamental design for a musical toy, substantially as shown.
